(57) CLAIM
The ornamental design for a fishing rod guide, as shown and described.

DESCRIPTION

FIG. 1 is a perspective view of a fishing rod guide showing my new design;

FIG. 2 is a perspective view of two fishing rod guides of FIG. 1 on a fishing rod showing an environment of use;

FIG. 3 is a right elevation view of the fishing rod guide of FIG. 1, a left side elevation view being a mirror image of FIG. 3;

FIG. 4 is a top plan view thereof;

FIG. 5 is a bottom plan view thereof; and,

FIG. 6 is a front elevation view thereof, a rear elevation view being a mirror image of FIG. 6.

The broken lines shown represent unclaimed subject matter and form no part of the claimed design.
